(57) **CLAIM**

We claim the ornamental design for an arrangement of wires for electrocuting flies, as shown and described.

DESCRIPTION

FIG. 1 is a top front right perspective view of an arrangement of wires for electrocuting flies showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Electric current passes through a fly when a fly contacts a pair of wires, thereby killing the fly.
